CONTROL OF THE SWASHPLATE OF A BARREL
PUMP BY ROCKER-ARMSGeorges Boulet, Toulouse, France, assignor to Société à
Responsabilité Limitée: Recherches Etudes Production

Filed Apr. 19, 1962, Ser. No. 188,654

Claims priority, application France May 5, 1961
7 Claims. (Cl. 74—60)

The present invention relates to barrel pumps in which an oblique plate governs the travel of the pistons of the pump. In order to regulate the rate of delivery and/or the pressure supplied by the pump, it is well known that the obliquity of this plate must be made variable, and the invention has for its object a system of control of this obliquity of the plate.

The control of obliquity of the plate according to the invention is characterized by the action on the plate of two rocker-arms which are themselves mechanically operated, for example by the pistons of two jacks, by two push-rods, by two cams, etc., these rocker-arms being so arranged as to reduce the transverse friction to a minimum and to maintain the lines of action of the forces in the vicinity of the axes of their mechanical controls.

One embodiment of the control according to the invention will be described with reference to FIGS. 1 and 2 of the accompanying drawings, which are given by way of example only and not in any limitative sense. In these drawings:

FIG. 1 is a partial cross-section of the pump taken along the line I—I of FIG. 2;

FIG. 2 is a section taken along the broken line II—II of FIG. 1;

FIGS. 3, 4 and 5 are diagrams illustrating the contours and the construction of cams employed in this application.

FIG. 1 shows only the portion of the pump which is concerned in the present invention.

The pump comprises a casing 1, a driving shaft 2 in said casing driving the barrel 3 with the piston 4. Each piston 4 is provided with a swivel 5, the travel of which is controlled by a ring 6 driven in rotation and having shoes with flat faces in frictional contact with the oblique swash-plate 7. The plate 7 is carried in known manner by two pivot pins 8 and 9 which permit its obliquity to be varied. According to the invention, this obliquity is controlled by two jacks 10 and 11, acting on the plate 7 through the intermediary of rocker-arms 12 and 13. The jack 10, is composed of a cylinder 14 and a piston 15 and is supplied with pressure fluid through a conduit system 16 through the annular groove 17, the bore 18, the chamber 19 and the bore 20. In the same way, the jack 11, composed of cylinder 21 and the piston 22 is supplied with pressure fluid through a conduit system 23 through the annular groove 24, the bore 25, the chamber 26 and the bore 27 (in the rear position of the piston). The supply of the jacks 10 and 11 by the conduit system 16 and 23 is effected by any suitable system of regulation control. The rocker-arms 12 and 13 pivot on shafts 28 and 29 supported in the casing 1. The shafts 28 and 29 are preferably mounted in a rotating ring, formed in one or two parts, which always ensures a straight-line contact between the bearing surfaces and rollers which will be described later, and the surfaces of the members with which the said bearing surfaces and rollers co-operate.

The rocker-arms 12 and 13 are actuated by the pistons 15 and 22, preferably through the intermediary of rollers 30 and 31. The rocker-arms 12 and 13 act on the plate 7 through the bearing surfaces 32 and 33, which cooperate respectively with the bearing surfaces 34 and 35 of the plate 7. The co-operating surfaces 32 and 34

on the one hand and 33 and 35 on the other are calculated and formed in the same way as the profiles of gear teeth, preferably as the involute of a circle, for example as ground, corrected teeth as shown in FIG. 3.

In FIG. 3, the line of action 36—37 of the piston 15 of the jack 10 and the line of action 38—39 of the piston 22 of the jack 11 are respectively chosen as lines of pressure of the conventional outline of the involute of a circle. The plate 7 is shown at its mean position of inclination, the extreme positions being shown at 40 and 41. There is thus obtained a rolling action without sliding and therefore without friction, of the two rocker-arms 12 and 13 on the plate 7. Furthermore, the result is also obtained that the forces are respectively applied along the lines 36—37 and 38—39, that is to say along the lines of action of the jacks 10 and 11, thus avoiding any oblique force and corresponding abnormal friction and wear.

The invention provides for the profiles to be corrected so as to take account of deformations of tooth form, and eventually so as to ensure equal travel of the two jacks 10 and 11 when their operation makes this necessary. The invention is equally well applicable however to two jacks having unequal travel, to two jacks having pistons of different diameters, or to two push-rods or two cams actuated in any known manner.

In FIG. 4, the lines *a* and *b* represent the limits of the bearing surfaces 34 and 35 of the surface of the plate 7 which cooperate with the bearing surfaces 32 and 33 of the rocker-arm. 42 and 42a, 43 and 43a, are the flanks of the tooth, rounded by the milling of the plate.

Instead of machining the bearing surfaces 34 and 35 on the plate 7 itself, as indicated above, the invention provides that these ground surfaces may be machined on separate parts secured to the plate as shown in FIG. 5, given by way of example and without limitation. A milled portion 44, formed in the plate 7, receives the separate piece 45. This piece 45 is provided with a centering lug 46 engaged in a corresponding hole in the plate. On the piece 45, the surface 34 is machined, which co-operates with the bearing surface 32 of the rocker-arm.

The invention also contemplates that the rollers and the bearing surfaces of the rocker-arms may be interchanged one with the other, the rollers being placed on the plate side and the bearing surfaces on the jack side, or that the rollers on the jack side may be replaced by bearing surfaces similar to those described and also cooperating with bearing surfaces of corresponding profile, formed on the pistons of the jacks.

What I claim is:

1. A pump of the barrel type with a variable output comprising a plate supported for rotation about a transverse axis perpendicular to the axis of rotation of the pump, flat faces of shoes in frictional contact with the plate, pistons supported for reciprocal movement, means swivel mounting said shoes on said pistons, a thrust member on each side of said transverse axis adapted to transmit thrust force to said plate in a direction parallel to the axis of rotation of the pump to regulate inclination of the plate and in consequence thereof travel of the pistons, a transmission member between each said thrust member and said plate movable in rotation about an axis of rotation parallel to the axis of rotation of the plate and including two bearing surfaces respectively tangent to the thrust member and to the plate at points of contact lying on a line substantially parallel to said transverse axis, each said thrust member and plate including a bearing surface at least one of which is in contact with a bearing surface of the transmission member and which latter surfaces have profile contours corresponding to the flanks of two teeth of the same gear-wheel.

2. A pump as claimed in claim 1, in which a bearing surface of the transmission member and the cooperating surface of the plate have respectively the profiles of the flanks of the teeth of two wheels of a gear, having axes corresponding respectively with the axes of rotation of the transmission member and of the plate.

3. A pump as claimed in claim 2, in which the bearing surface of the transmission member on the thrust member is a roller having an axis of rotation which is parallel to the axis of rotation of said transmission member.

4. A pump as claimed in claim 2, in which the bearing surface of the transmission member and that of the thrust member are respectively that of the flank of a tooth of a toothed wheel having an axis which is coincident with the axis of rotation of said member and that of the flank of a tooth of a toothed rack extending parallel to the axis of the pump, and engaging with said wheel.

5. A pump as claimed in claim 1, in which the bearing surface of said thrust member and the co-operating surface of said transmission member are respectively that of the flank of a tooth of a toothed rack extending parallel to the axis of the pump and that of a wheel having an

15 5 axis coincident with that of the transmission member and engaging with said toothed rack, the bearing surface of said transmission member cooperating with the plate being the surface of a roller having an axis parallel to the axis of rotation of said transmission member.

6. A pump as claimed in claim 1, in which said thrust member is the piston of a hydraulic jack.

7. A pump as claimed in claim 1 comprising a separate part having a surface constituting the said one bearing surface which has a contour corresponding to the flank of the gear teeth, said separate part including a centering lug for being accommodated in the element which is to have the bearing surface corresponding to the flank of the gear teeth.
